No. 868,965.

PATENTED OCT. 22, 1907.

C. B. P. CARVER.
GIN CYLINDER.
APPLICATION FILED SEPT. 5, 1905.

UNITED STATES PATENT OFFICE.

CALVIN B. P. CARVER, OF BRIDGEWATER, MASSACHUSETTS.

GIN-CYLINDER.

No. 868,965.

Specification of Letters Patent.

Patented Oct. 22, 1907.

Application filed September 5, 1905. Serial No. 276,925.

To all whom it may concern:

Be it known that I, CALVIN B. P. CARVER, of Bridge-
water, in the county of Plymouth and State of Massa-
chusetts, have invented certain new and useful Im-
5 provements in Gin-Cylinders, of which the following is
a specification.

This invention relates to saws for cotton gins, and
consists in the construction of a saw-cylinder in which
the saws are mounted.

10 Figure 1 in side elevation, shows a saw constructed
in accordance with my invention, the metal of the cyl-
inder being broken away for convenience, showing an
arrangement of saws with relation to the cylinder and
one another. Fig. 2 is an end elevation of the con-
15 struction shown in Fig. 1. Fig. 3 is a longitudinal
sectional view of a saw-cylinder shown in Fig. 1, show-
ing the arrangement of the hubs of the cylinder with
relation to the driving-shaft and the grooves in said
cylinder for receiving and holding the saws. Fig. 4 is
20 a cross-sectional view on line 4-4 of Fig. 3, showing
the lugs in a saw-cylinder against which the saws are
held. Fig. 5 is a side elevation of a portion of a gin
saw. Fig. 6 is a like view, showing the method of con-
25 structing the gin saw in two parts. Fig. 7 is a perspec-
tive view of one of the wooden wedges by which the
saws are fastened.

The same reference characters indicate the same parts
in all of the figures.

1 represents a driving cylinder for a gang of saws used
30 in ginning cotton or linting cotton seeds. As, con-
structed prior to my invention, the several saws for
making up the gang for use in said process have been
slid upon a shaft and spaced apart by blocks. Such
construction is common and requires no particular
35 description. The use of the shaft and the space block
requires a great deal of time for the proper mounting
and spacing of the saws and this arrangement is subject
to a number of infirmities in practical operation, re-
quiring a gage in which the saws are placed at the time
40 of their being spaced on the shaft with space blocks.
The saws are liable to more or less displacement due
to unevenness of the space blocks and the expansion or
contraction by moisture, and the difficulty of replac-
ing any of the saws. By my invention all these diffi-
45 culties are overcome. I secure upon the shaft 1, a saw-
cylinder 2, comprising in the form shown, two hubs
3, 3, keyed upon the shaft by a spline 4. The hubs 3
are formed with spokes 5 which support a cylinder-
shaped shell 6. The cylinder upon its periphery is
50 formed with a plurality of longitudinal ribs 7, 7, there
being ten of such ribs in the form shown, although
this number may be varied, if desired. Each of the
ribs 7 is formed with a series of slots 8, 8, a slot in one
rib being in the same vertical plane as the comple-
55 mental slot in the other ribs, and being of sufficient
size to receive the lugs hereinafter described, on the

inner circumference of the saws. The ribs 7, 7, as
shown, are separated by a space 9 for a purpose herein-
after described.

Instead of forming the saw as heretofore, with a 60
uniform inner circumference, I form the inner circum-
ference with a series of lugs 11, separated by spaces
12, each space 12 being of a size to receive a rib 7 of
the cylinder 2, and each lug 11 being of a size to fit
and slide in a space 9, and also to enter a slot 8. One 65
or more of said lugs is formed with a tooth, as 13, adapt-
ed to project down below the bottom of a slot 8 and
engage the wall 14, below said slot, the tooth 13 serv-
ing as a driving connection between the cylinder and
the saw. Any other means may be employed for ef- 70
fecting the driving connection between the saw and
cylinder.

In practice, a saw constructed as in Fig. 5, is slid
over the cylinder 2 with its lugs 11 in the space 9 be-
tween the ribs 7, and with its space 12 over the ribs 7, 75
this arrangement permitting the saws to be slid from
one end to the other of the cylinder.

Referring to Fig. 1, assuming that no saws are on the
cylinder, the saw now at the left of the cylinder will
be slid on until its lugs 11 come opposite the grooves 8 80
at the left end. The saw would then be given a suffi-
cient turn to bring its lugs 11 into the space 9. There-
after, a wooden wedge 20, is driven down between each
lug 11 and at the side of a tooth 30, thereby firmly
binding the saw in place, the left-hand end of the 85
tooth 30 serving as a gage for the accurate seating of the
saw. Thereafter, the other saws are assembled in the
same way, there being no necessity in spacing the saws
apart by the space blocks, the teeth 30 not only serving
as a spacing means, but also as means for binding the 90
saws to the cylinder.

Instead of forming the saw as in Fig. 5, I may form
the saw in two parts, as shown in Fig. 6, one of the parts
being formed with an interlocking member, 50, adapted
to coact with a complementary interlocking member, 95
60, on the other part. While this form of saw may be
used generally, I have designed it particularly for use
in repairing, when one of the saws in the gang becomes
broken. I can by my improved form of saw cylinder
easily and quickly insert the form of saw shown in Fig. 100
6, interlocking the same and fastening it in its proper
place between the teeth 30.

Having thus explained the nature of my invention
and described a way of constructing and using the
same, though without attempting to set forth all of 105
the forms in which it may be made, or all of the modes
of its use, what I claim and desire to secure by Letters
Patent is:—

1. A gin-cylinder comprising a cylinder formed with a
series of longitudinal ribs separated by spaces, each of said
ribs being slotted to form teeth, the teeth and slots of one
rib being arranged in the same vertical plane as the com- 110

- plemental teeth and slots of the other ribs, a saw formed upon its interior circumference with a series of lugs separated by spaces corresponding to the ribs and spaces on the cylinder, the lugs of the saw being arranged in grooves in the ribs, and means for securing the parts in place.
2. A gin saw cylinder comprising a hub formed with a series of longitudinal ribs, each of said ribs being slotted to form a series of teeth, the teeth and slot of one rib lying in the same radial plane as the complementary teeth and slot of the other ribs.
3. A gin cylinder comprising a barrel formed with a series of longitudinal ribs, each of which is slotted to form a series of teeth, the teeth and slots of one rib being

arranged in the same radial plane as the teeth and slots of the other rib, a gin saw formed upon its interior circumference with a series of lugs separated by spaces, said lugs being arranged in position in the slots and ribs of the barrel, and a driving connection between the barrel and the saw.

In testimony whereof I have affixed my signature, in 20 presence of two witnesses.

CALVIN B. P. CARVER.

Witnesses:

E. A. ALLEN,
P. W. PEZZETTI.
